UNITED STATES PATENT OFFICE.

DAVID G. LORRAINE, OF LOS ANGELES, CALIFORNIA.

OIL AND GAS SEPARATOR.

Application filed May 26, 1924. Serial No. 715,894.

This invention is an oil and gas separator having valvular controls for the gas and oil respectively, the valvular control for the gas being positioned inside the tank of the separator for protection thereof, with the valvular control for the oil mounted on the exterior of said tank, so that access may be readily had thereto for draining said valve of accumulated sand or other foreign matter.

It is a further object of the invention to provide a separator having the valvular controls for the gas and oil arranged as described, with said valvular controls operated by a common float mechanism which is movable responsive to variations in the oil level in the separator.

It is a still further object of the invention to provide a construction wherein the heavier constituents of a flow will be discharged in a quiescent state into a settling chamber, so that the gas may readily rise therefrom, and the lighter constituents which readily separate from the incoming flow, will, without first passing through said settling chamber, be suitably agitated for separation of any oil remaining mixed therewith, and then discharged through the gas outlet along with the gas rising from the settling chamber.

The invention will be readily understood from the following description of the accompanying drawings, in which:

Fig. 1 is a vertical section through a separator constructed in accordance with the invention.

Fig. 2 is a vertical section on the line 2—2 of Fig. 1.

Fig. 3 is a horizontal section on the line 3—3 of Fig. 1.

The separator comprises a closed casing 1 having a sand discharge 2 at the bottom thereof, and having a man-hole provided with a removable cover 3 at the top of said casing.

A transverse vertical partition 4 is arranged in the upper portion of the casing at one side thereof, the sides of said partition meeting the side wall of the casing to form a space separated by said partition from the main portion of the casing. This space is closed at its top by a horizontal partition 5 extending from partition 4 toward the casing wall and connected to an annular flange 6 mounted in casing 1 above partition 4 as will be hereinafter described.

The partition 4 extends downwardly to a point somewhat below midway of the height of the casing, and the side space formed by the partition is open to the main portion of the casing below said partition.

An annular casing 7 of appreciably less diameter than casing 1, is concentrically mounted in the latter at the upper portion thereof above partition 4, the annular flange 6 extending from the lower edge of casing 7 toward the wall of casing 1, with the periphery of said flange spaced slightly from the casing wall so as to form an annular restricted opening 8 beyond said flange.

An annular flange 9 extends from the upper edge of casing 7 to the wall of casing 1, and is spaced below the top of casing 1 so as to form a space for valve mechanism to be hereinafter described.

The construction as thus described provides an annular chamber between casings 1 and 7 with the ends of said chamber closed by flanges 6 and 9, the said chamber being hereinafter referred to as the cleaning chamber. The construction also provides a chamber to be designated the gas chamber, inside of casing 7, and open at its upper end to the portion of casing 1 above the cleaning chamber, and opening at its lower end directly into main casing 1 below the cleaning chamber and in front of partition 4, said portion of the main casing forming an unobstructed continuation of the settling chamber in the lower end of the separator below the partition.

A pipe 10 is mounted in an opening in flange 6, so as to communicate with the side space formed by partitions 4 and 5 and said flange, the upper end of said pipe extending into the cleaning chamber and terminating in a horizontal nozzle which is circumferentially disposed with relation to the vertical walls of the cleaning chamber. The nozzle opening is preferably horizontally restricted as shown in Fig. 2.

A discharge from the cleaning chamber to the gas chamber is formed by cutting a vertically extending lip in the wall of casing 7 and bending said lip inwardly to form an elongated opening 11, said discharge opening being arranged slightly in rear of nozzle 10 with relation to the direction of circumferential discharge from said nozzle.

The space in back of partition 4 is an inlet passageway for the flow from an oil well, the flow inlet means comprising a pipe 12

extending through the casing wall and into said space near the top thereof, with the portion of said pipe in said casing being horizontally disposed and having a lateral opening in the underside thereof.

As the flow from an oil well enters the inlet passageway through pipe 12, the lighter gas which immediately separates from the heavier constituents of the flow, will rise in back of partition 4 and be discharged through nozzle 10 into the cleaning chamber, and the remainder of the flow will gravitate through the inlet passageway to the settling chamber.

15 In the settling chamber the heavier sand and water mixed with the flow, will settle below the oil which is maintained in a quiescent state, and the gas which is mixed with the oil will rise into the gas chamber.

20 The gas discharged through nozzle 10 will cause rotary agitation in the cleaning chamber, so as to separate by centrifugal action, any oil remaining mixed with the gas, and the oil thus liberated will return to the settling chamber through the restricted annular opening 8 at the periphery of flange 6, while the dry gas after passing around the cleaning chamber, will be discharged through opening 11 into the gas chamber.

25 An oil outlet 13 communicates with the settling chamber through the wall of casing 1, and a valve 14 controlling said oil outlet, is mounted on the exterior of the casing and is adapted to have any suitable oil pipe connected thereto for removal of the oil.

30 A gas outlet conduit 16 extends through the wall of casing 1 above the cleaning chamber, and a valvular control 15 is mounted on said conduit inside of the tank, with the outer end of said conduit adapted for connection to any suitable gas line.

35 By this arrangement valve 15 which is not subjected to excessive wear or clogging action and therefore does not require frequent inspection or repair, will be protected against injury by its position inside of the separator, and valve 14 for the oil line, which is liable to become clogged by sand or the like, is readily accessible upon the exterior of the separator, since it requires close inspection and replacement of parts.

40 Valve 14 is actuated by a rocker arm 17 extending into casing 1 through oil outlet 13, and said valve is preferably counterbalanced by a weighted arm 18 fixed to the operating shaft thereof; and the valve 15 for the gas discharge is also operated by a rocker arm 19.

45 The rocker arms for the valves are connected by links 22 to arms 21 which are pivotally mounted in casing 1 and connected to the respective ends of a float 20. The float is supported by arms 21 approximately midway of the height of the separator and in front of partition 4, and will rise and fall

responsive to variations in the oil level in casing 1. The movement of the float will in turn actuate valves 14 and 15 through the operating connections, for regulating discharge of oil and gas from the separator in accordance with the level of the flow with relation thereto.

50 The construction as thus described provides a convenient and practical arrangement of the valvular controls for the oil and gas, and also provides for efficient separation of the oil from the gas, by the provision of a cleaning chamber arranged for rotary agitation therein.

55 It will be apparent that various changes may be made in the construction, combination, and arrangement of parts as thus described without departing from the spirit of the invention.

I claim:

1. A device of the character described comprising a settling chamber, a gas chamber, a discharge from said settling chamber, a valvular control for said discharge at the exterior of the device, a gas discharge from said gas chamber, a valvular control for said gas discharge inside of said gas chamber, a float movable in accordance with the level of a flow relative to the device, and operating connections between the float and the respective valvular controls.

2. A device of the character described comprising a tank having a flow inlet and forming a settling chamber and a gas chamber, a discharge from said settling chamber, a valvular control for said discharge at the exterior of said tank, a gas discharge from said gas chamber, a valvular control for said gas discharge inside said tank, a float movable in accordance with the level of a flow relative to the device, and operating connections between the float and the respective valvular controls.

3. A device of the character described comprising a tank forming a settling chamber and a gas chamber, a discharge from said settling chamber, a valvular control for said discharge at the exterior of said tank, a gas discharge conduit leading from said gas chamber through the wall of said tank, a valvular control for said conduit supported thereby inside said tank, a float in said tank, and operating connections between said float and the respective valves.

4. A device of the character described having a flow inlet and comprising a settling chamber, a gas chamber, and a cleaning chamber open to said flow inlet and arranged for circumferential movement therein of the lighter portion only of the flow from said flow inlet.

5. A device of the character described having a flow inlet and comprising a settling chamber, a gas chamber, an annular cleaning chamber, and a conduit open to said flow

- inlet and discharging into said annular chamber circumferentially thereof, said cleaning chamber having a port adapted for discharge therefrom to said gas chamber 5 at a tangent to said annular cleaning chamber.
6. A device of the character described comprising a tank forming a settling chamber and a gas chamber above the same, and 10 an annular cleaning chamber in said tank around said gas chamber arranged for circumferential movement therein of the lighter portion only of a flow into said tank.
7. A device of the character described 15 comprising a tank having a flow inlet and forming a settling chamber and a gas chamber below and above said flow inlet respectively, and an annular cleaning chamber in said tank around said gas chamber having an intake open to the flow inlet and a discharge open to the gas chamber, the relative position and arrangement of the intake and discharge preventing any flow from the cleaning chamber to the gas chamber 20 without first passing around substantially the entire cleaning chamber.
8. A device of the character described comprising a tank forming a settling chamber and a gas chamber above said settling 25 chamber, a vertical inlet passageway at the side of said tank open at its lower end to said settling chamber, and an annular cleaning chamber in said tank around said gas chamber and open to the upper portion of said vertical inlet passageway and discharging 30 into said gas chamber.
9. A device of the character described having a flow inlet and comprising a settling chamber, a gas chamber, and a cleaning 35 chamber adapted to receive the lighter portion only of the flow from said flow inlet, said cleaning chamber having a discharge into said gas chamber and an opening at the bottom thereof for discharge of the 40 heavy constituents of the flow to said settling chamber.
10. A device of the character described 45 having a flow inlet and comprising a settling chamber, a gas chamber, and an annular cleaning chamber open to said flow inlet and discharging into said gas chamber, said cleaning chamber having a restricted opening at the outer circumference of the base thereof for discharge of the heavy constituents of the flow to said settling chamber.
11. A device of the character described 50 comprising a settling chamber, a gas chamber, a discharge from said settling chamber, a valvular control for said discharge at the exterior of said settling chamber, a gas discharge conduit leading from said gas chamber through the wall thereof, a valvular con- 55 trol for said conduit inside of said gas chamber, a float movable in accordance with the level of a flow relative to the device, and operating connections between the float and the respective valvular controls.
12. A device of the character described 65 having a flow inlet and comprising a settling chamber, a gas chamber, a cleaning chamber open to said flow inlet and arranged for circumferential movement therein, a discharge from the settling chamber having a valvular control, a float movable in accordance with the level of a flow relative to the device, and an operating connection between 70 said float and the valvular control.
13. A device of the character described 75 having a flow inlet and comprising a settling chamber, a gas chamber, an annular cleaning chamber, and a conduit open only to the lighter constituents of the flow at said flow inlet and discharging into said annular cleaning chamber circumferentially thereof.
14. A device of the character described 80 having a flow inlet and comprising a settling chamber, a gas chamber, and an annular cleaning chamber, said cleaning chamber having a port adapted for discharge therefrom to said gas chamber at a tangent to 85 said annular cleaning chamber.
15. A device of the character described 90 having a flow inlet and comprising a settling chamber and a gas chamber below and above said flow inlet respectively, and a cleaning chamber open to said flow inlet and discharging into said gas chamber only after 95 passage of all of the flow in the cleaning chamber around substantially the entire circumference thereof.
16. A device of the character described 100 comprising a tank forming a settling chamber and a gas chamber above said settling chamber, a vertical inlet passageway in said tank open at its lower end to said settling chamber, and a cleaning chamber in said tank and open to the upper portion of said vertical inlet passageway and arranged for 105 circumferential movement therein.
17. A device of the character described 110 having a flow inlet and comprising a settling chamber, a gas chamber, and a cleaning chamber open to said flow inlet and arranged for circumferential movement therein and discharge into said gas chamber, said cleaning chamber having a closed base with an annular opening therein for discharge of the heavy constituents of the flow to said settling chamber.
- In testimony whereof I have affixed my signature to this specification.

DAVID G. LORRAINE.
